UNITED STATES PATENT OFFICE.

JARED MARIS, OF COLUMBUS, OHIO.

DESIGN FOR THE ORNAMENTATION OF WHEEL-HUBS.

SPECIFICATION forming part of Design No. 16,363, dated November 3, 1885.

Application filed July 22, 1885. Serial No. 172,343. Term of patent 3½ years.

To all whom it may concern:

Be it known that I, JARED MARIS, a citizen of the United States, residing at Columbus, in the county of Franklin and State of Ohio, 5 have invented and produced a new and original Design for Flanges for Wheel-Hubs, of which the following is a specification, reference being had to the accompanying drawing, forming part thereof.

10 My design is for the ornamentation of the flange of a wheel-hub; and it consists in a wavy line made up of a series of reverse curves on the outer face of the flange, near the periphery thereof.

15 The accompanying drawing represents a view in elevation of a shell-band embodying my invention.

The leading feature of my design consists

in a circular or cylindrical flange, A, of a shell-band for hubs, having a wavy line on the outer 20 face of said flange, near the periphery. This wavy line is made up of a series of reverse curves of any desired size.

Having fully described my design, what I claim as new, and desire to secure by Letters 25 Patent, is—

In a design for the flange of a wheel-hub, the ornamentation of the same, consisting in a wavy line made up of a series of reverse curves on the outer face of the flange, near 30 the periphery thereof.

JARED MARIS.
